ROOM COOLER

Carlos F. Wheaton, Minneapolis, Minn.

Application September 29, 1937, Serial No. 166,365

15 Claims. (Cl. 62—133)

My present invention has for its object to provide a simple and highly efficient room cooler that can be manufactured at a relatively small cost.

To increase the efficiency of the improved room cooler, I provide means for re-circulating air therein, as will hereinafter appear. In connection with this cooler, I embody therein a storage chamber which acts as an air re-circulating chamber.

To the above end, generally stated, the invention consists of the novel devices and combination of devices hereinafter described and defined in the claims.

15 In the accompanying drawing, which illustrates the invention, like characters indicate like parts throughout the several views.

Referring to the drawing:

Fig. 1 is a view principally in vertical section taken substantially on the line 1—1 of Fig. 2;

Fig. 2 is a view in transverse vertical section taken on the line 2—2 of Fig. 1;

Fig. 3 is a view principally in transverse vertical section taken on the line 3—3 of Fig. 1; 25 and

Fig. 4 is a fragmentary detail view showing the use of a single fan for supplying air to the cooler and re-circulating the same.

Referring first to the invention shown in Figs. 30 1 to 3, inclusive, the numeral 5 indicates an insulated portable cabinet having at one end a heat exchange compartment 6, which occupies the greater part of the cabinet, and also having at its other end a storage chamber 7, which acts 35 also as an air re-circulating chamber. Within the cabinet 5, below the storage chamber 7 is a fan housing 8. The cabinet 5 has door openings 9 and 10, the former of which affords access to the compartment 6, and the latter to a storage 40 chamber 7. These door openings 9 and 10 are normally closed by doors 11 and 12, respectively, and which doors are insulated in the same manner as the walls of the cabinet 5. Said cabinet 5 is mounted on casters 13 to permit easy movement thereof from place to place.

Ice is used as a cooling medium for the improved room cooler and this ice is supplemented by the water from the melted ice.

50 Removably mounted in the compartment 6 is a plurality of individual heat exchangers 14, as shown six, each of which is a metallic bucket-like ice container. In each heat exchanger 14 is a cake of ice *x* and water *y*. These heat exchangers 14 are, as shown, arranged in lower, upper and intermediate pairs, and each pair is

slidably mounted on a pair of guide rails 15 for movement through the respective door opening 9. Said rails 15 are, as shown, angle bars having their vertical flanges turned downwardly and secured to the sides of the cabinet 5, and these 5 horizontal flanges are turned toward each other and slidably support the respective heat exchangers 14 thereon.

The width of the heat exchangers 14 is such as to leave vertical air spaces between the sides 10 of said heat exchangers and the side walls of the compartment 6. Said heat exchangers 14 are also horizontally spaced on the guide rails 15 to leave vertical air spaces between the heat exchangers 14 and the ends of the cabinet 5 15 and also between said heat exchangers. The guide rails 15 support the heat exchangers 14 with horizontal air spaces between the lowermost heat exchangers and the bottom of the compartment 6, between the uppermost heat exchangers and the top of said compartment, and between the several pairs of heat exchangers 14.

In the top of the cabinet 14, substantially directly above the uppermost right-hand heat exchanger 14, is a displaceable cover 16 having a 25 grilled air escape opening 17. An air passage-way 18 in the partition 18 between the compartment 6 and the storage chamber 7 permits a flow of air from the compartment 6 into the storage chamber, and it is at this point that the 20 re-circulation of air starts.

Mounted in the housing 8 are twin fans independently designated by the numerals 20 and 21, respectively, and driven by a single electric motor 22 mounted therebetween. It is, of course, 35 understood that the fans 20 and 21 may be singly and individually driven by an electric motor.

The fan 20 is constructed and arranged to take air from the room, in which the cooler is 40 placed, through an air intake opening 23, at the bottom of said cooler, and discharge the same into the compartment 6, below the heat exchangers 14, through an opening 24 in the partition 18. The fan 21 is constructed and arranged to 45 take air from the storage chamber 7, through a duct 25 leading therefrom, and discharge the same into the compartment 6 through an opening 26 in the partition 18 below the heat exchangers 14.

On the door 11 and the partition 18 are pairs 50 of opposing deflectors 27 for directing part of the upwardly moving air between the vertically spaced pair of heat exchangers 14. In the upper left-hand corner of the compartment 6 is a de- 55

flector 28 constructed and arranged to direct part of the upwardly moving air horizontally over the uppermost heat exchangers 14 and toward the air escape opening 17 and the air passageway 19. Obviously, from the time air is discharged into the compartment 6 to the time it reaches the air escape opening 17 and the air passageway 19, it will have travelled over all four sides and the bottom of each heat exchanger 14, as well as over the ice and water in the open tops thereof.

By varying the speed of the fans 20 and 21, the volume of air forced over and around the heat exchangers 14 may be varied, at will, to hasten or retard the melting of the ice, to a certain extent, and thereby change the temperature of the chilled air which escapes from the cooler into the room.

Within the storage chamber 7 are shelves 29 on which bottles or other articles to be kept cool may be placed. By removing the cover 16, a bottle or other article may be placed in the underlying heat exchanger 14 for the purpose of chilling the same.

25 The mounting of the heat exchangers 14 is such that they can be easily removed from the cooler for the purpose of emptying the water therefrom and then refilling with cakes of ice.

Referring now to the invention as shown in Fig. 4, the numerals 30, 31, and 32 indicate, respectively, the cooler cabinet, its air re-circulating chamber and the motor housing. In this modification, a single fan 33, driven by an electric motor 34, is used for supplying the cooler with air from the outside thereof, and for re-circulating the air in the cooler.

Air is drawn into the motor housing 32 from outside of the cooler by the fan 33, through an air intake opening 35 in the cabinet 30, and 40 also from the storage chamber 31 through an air intake opening 36 in the bottom of said chamber. This air in the housing 32 is drawn into the fan 33 and discharged thereby into the heat exchanger compartment 37 through an opening 38 in the partition 39. It will thus be seen that a single fan draws part of its air supply from outside of the cooler and part thereof from the storage chamber 31, and re-circulates part of the air it discharges into the compartment 37 downward through the storage chamber 31 from the air passageway at the upper end thereof.

The above described device is capable of various modifications within the scope of the invention herein disclosed and claimed.

55 Referring again to the structure shown in Figs. 1 to 3, inclusive, each heat exchanger 14 is provided with a pair of handles 14' by which it may be carried. At the bottom of the compartment 6 is a normally closed drain 6' for removing condensation accumulated on the bottom of said compartment.

What I claim is:

1. A room cooler comprising a cabinet having a heat exchanger compartment and an air re-circulating chamber, a heat exchanger in the form of an ice container in said compartment, said compartment having an air passageway leading to said chamber, a motor-driven fan for taking air from said chamber and discharging the same into said compartment and an air escape port opening out of the cabinet for discharging air cooled in the heat exchanger compartment.

2. A room cooler comprising a cabinet having 75 a heat exchanger compartment and an air re-

circulating chamber, a heat exchanger in the form of an ice container in said compartment, said compartment having an air passageway leading to said chamber, a motor-driven fan constructed and arranged to take part of its air supply from outside of the cooler and part thereof from the re-circulating chamber and discharge the air into said compartment and an air escape port opening out of the cabinet for discharging air cooled in the heat exchanger 10 compartment.

3. A room cooler comprising a cabinet having a heat exchanger compartment and an air re-circulating chamber, a heat exchanger in the form of an ice container in said compartment, 15 said compartment having an air escape opening and an air passageway leading to said chamber, a motor-driven fan constructed and arranged to take air outside of the cooler and discharge the same into the compartment, and a second 20 motor-driven fan constructed and arranged to take its air supply from the re-circulating chamber and discharge the same into the compartment.

4. The structure defined in claim 1 in which 25 air discharged by the fan into the compartment is directed under the heat exchanger.

5. A room cooler comprising a cabinet having a heat exchanger compartment and an air re-circulating chamber, a plurality of heat exchangers in said cabinet, each of which is in the form of an ice container, said heat exchangers being spaced from the internal surfaces of the compartment and each other for the circulation of air therearound and therebetween, said compartment having an air escape opening and a passageway leading to said chamber, and a motor-driven fan for taking air from said chamber and discharging the same into said compartment.

6. The structure defined in claim 5 in which 40 the heat exchangers are removable from their compartment.

7. A room cooler comprising a cabinet having a heat exchanger compartment and a storage compartment, said storage compartment affording 45 an air re-circulating chamber, a heat exchanger in said compartment in the form of an ice container, said compartment having an air escape opening and an air passageway leading to said chamber, and a motor-driven fan for taking air 50 from said chamber and discharging the same into said compartment.

8. A room cooler comprising a cabinet having a heat exchanger compartment and an air re-circulating chamber, a heat exchanger in the compartment in the form of an ice container, 55 said compartment having an air escape opening and an air passageway leading to said chamber, a motor-driven fan for taking air from said chamber and discharging the same into said compartment, and a deflector for directing air over the heat exchanger and toward the air passageway.

9. A room cooler comprising a cabinet having a heat exchanger compartment and an air re-circulating chamber, upper and lower pairs of heat exchangers in said cabinet, each of which is in the form of an ice container, said pairs of heat exchangers being spaced, the one above the other, said compartment having an air escape 70 opening and an air passageway leading to said chamber, a motor-driven fan for taking air from said chamber and discharging the same into said compartment, and two deflectors, one on each of opposite sides of said compartment for 75

directing air in opposite directions between the upper and lower pairs of heat exchangers.

10. A portable room cooler comprising a cabinet having a heat exchanger compartment and an air re-circulating chamber, a heat exchanger in the form of an ice container in said compartment, said compartment having an air passageway leading to said chamber, means for taking air from the compartment, re-circulating said air through the chamber and returning the same to the compartment and an air escape port opening out of the cabinet for discharging air cooled in the heat exchanger compartment.

11. The structure defined in claim 10 in which the room cooler has a plurality of heat exchangers spaced from the internal surfaces of the compartment and from each other for the circulation of air therearound.

12. A portable room cooler comprising a cabinet having a heat exchanger compartment and a storage chamber, a heat exchanger in the form of an ice container in said compartment, said compartment having an air escape opening and an air passageway leading to said chamber, and means for taking air from said compartment, re-circulating said air through the chamber, and returning the same to the compartment.

13. The structure defined in claim 12 in which the room cooler has a plurality of removable heat

exchangers spaced from the internal surfaces of said compartment and each other for the circulation of air therearound.

14. A portable room cooler comprising a cabinet having a heat exchanger compartment and a storage chamber, a plurality of removable heat exchangers, each of which is in the form of an ice container in the compartment, said compartment having an air escape opening and an air passageway leading to the chamber, and a motor-driven fan constructed and arranged to take part of the air supply from outside of the cooler and part thereof from the storage chamber and discharge the air into the compartment.

15. A portable room cooler comprising a cabinet having a heat exchanger compartment and a storage chamber, a plurality of removable heat exchangers, each of which is in the form of an ice container in the compartment, said compartment having an air escape opening and an air passageway leading to the chamber, a motor-driven fan constructed and arranged to take air outside of the cooler and discharge the same into the compartment, and a second motor-driven fan constructed and arranged to take its air supply from the storage chamber and discharge the same into the compartment.
